NURSING DOLL

George W. Wood, Gordon McDougall Shaw, and
James Alan Scott, Magog, Quebec, Canada

Application July 30, 1949, Serial No. 107,664

2 Claims. (Cl. 46—141)

1

This invention relates to dolls and more particularly to dolls incorporating features adapting them to simulate certain natural functions.

While dolls adapted to receive and discharge liquids are well known in the art, most of these present certain disadvantages in that the liquid is generally fed and discharged solely by gravity with no provision made for storage of the liquid so that the discharge occurs just as soon as the liquid passes through the doll's body. Others have been made so as to operate by providing some form of a suction device to draw liquid from a container, but again no attempt is made to retain the liquid within the body.

The present invention aims to provide an improved construction of a doll of this nature, that can receive, store, and discharge liquid as required, each function being under the control of the person handling the doll.

Accordingly, the present invention comprises a doll having mechanical means within the head and body adapting the doll to receive liquid from the nipple of a nursing bottle, store the liquid within the body, and discharge the liquid when desired.

More specifically, a preferred construction of a doll according to the invention comprises a hollow doll body including a hollow head adapted to house the mechanical means adapted to perform these various functions.

The body and head may be of any preferred form or of any desired material with the head being preferably removable from the body so as to facilitate installation of the various working parts.

The mechanical means activating the doll are preferably constructed as a complete unit which can be assembled outside of the body and inserted within the body and head as a unit. This is accomplished by providing a main supporting frame adapted for attachment within the body of the doll and having the various elements mounted on this frame.

The working elements of the doll consist essentially of a liquid receiving unit including a movable portion adapted to simulate the movements of the tongue, a liquid storage sac or bladder that includes a one-way valve inlet means so as to prevent return of the liquid to the receiving unit and a controlled outlet means so that the contents of the sac or bladder may be discharged as required. An eye moving and blinking device is also mounted on the main frame above the liquid receiving unit and is operatively connected to an actuating lever which also controls the movement of the depressing or tongue portion.

When installed within the body of the doll the

2

liquid receiving unit and eye moving unit is positioned within the head, the eyes fitting into the eye sockets of the doll and the liquid receiving unit being positioned behind a mouth opening.

5 The actuating lever is positioned within the doll body and is preferably provided with a disc-like end that is positioned so as to rest against the inner surface of the abdomen of the doll which is preferably constructed of a flexible material. 10 With this arrangement pressure on the abdomen of the doll actuates the lever which in turn actuates the movable depressor or tongue of the liquid receiving unit.

In operation, liquid is supplied from a nursing 15 bottle, the nipple of which is inserted in the mouth opening of the doll so as to extend within the liquid receiving unit. On actuation of the depressor portion of this unit as caused by the flexing of the abdomen portion of the doll, liquid 20 flows from the bottle into the liquid receiving unit when it is conveyed by a conduit to the storage sac positioned within the body of the doll. Preferably, the nursing bottle employed includes a valved nipple so as to minimize leakage when 25 the bottle is withdrawn or inserted in the liquid receiving portion of the doll.

The eye moving portion of the unit is connected by a ratchet and cam device to the main actuating lever so that the doll is adapted to simulate a slow 30 blinking of the eyes at intervals during the liquid receiving operation.

The outlet means of the storage sac is connected to the exterior of the doll's body by a conduit, and a check valve controlled by a lever extending exteriorly of the body is connected in the conduit so that the contents of the sac may be discharged as required.

With the present arrangement, the doll is adapted to receive liquid from a nursing bottle, slowly, and in a lifelike manner, due to the movements of the depressor or tongue portion, while the eyes blink in a manner simulating the actions of a human infant.

Having thus generally described the nature of 45 the invention, particular reference will be made to the accompanying drawing, and in which:

Figure 1 is a longitudinal section through a doll constructed in accordance with the invention.

50 Figure 2 is a view in front elevation of the internal mechanism of the doll as shown in Figure 1 with the body of the doll indicated in dotted lines.

Figure 3 is an enlarged detail view in perspective elevation to illustrate the eye moving mechanism of the apparatus.

55 Figure 4 is a longitudinal section of a doll cor-

responding to Figure 1 with the mechanism partially in section illustrating the operation of the liquid receiving unit.

Figure 5 is a sectional view of a preferred form of nipple employed in combination with the apparatus of the invention.

Figure 6 is a longitudinal section of a doll corresponding to Figure 4 illustrating the liquid receiving unit and eye moving mechanism in operation.

Figure 7 is a vertical section of a portion of the construction shown in Figure 1 to illustrate the construction and relative position of the liquid receiving chamber in more detail.

With particular reference to the drawings illustrating a preferred construction of the device, the doll comprises a body 10, a head 12, and having suitably attached arms and legs (not illustrated).

The body 10 and head 12 are hollow, and preferably made of a hard composition with the exception of the portion 14 forming the front of the abdomen which is of a flexible material, for example, rubber, or other resilient materials. As shown in Figures 1, 4, and 6, the mechanism of the doll is positioned within the interior of the body 10 and the head 12, the head 12 being preferably removable from the body 10 so as to facilitate insertion of the working elements.

The operating mechanism of the doll is mounted on a main supporting frame 20 that extends the length of the body 10 into the head 12. The liquid receiving portion of the apparatus includes a boxlike chamber 30 having an open end 31 positioned within the head 12 of the doll against the mouth opening 35. The chamber 30 is mounted on the upper end of the frame 20 and a lever member 32 that includes a depressor portion 34 is pivotally mounted to the frame 20 so that the portion 34 is adapted to move up and down in the open end 31 of the chamber 30. The lever member 32 also includes an extended portion 36 that extends rearwardly of the frame 20 and an offset lever portion 38 that is engaged by a main actuating lever 40.

The main actuating lever 40 is pivotally mounted intermediate its length to the supporting frame 20, the upper end 41 being adapted to engage the lever portion 38 of the member 32 with the lower end 43 provided with a pressure disc 44 that is adapted to rest against the flexible insert 14 in the front portion of the doll's body 10.

A coil spring 48 is connected between the lever member 32 and the frame 20 so as to normally urge the depressor portion 34 downwards and away from the upper portion of the chamber end 31, the downward motion being transmitted to the main lever 40 through the lever portion 38 so as to maintain the disc 44 in contact with the flexible body portion 14.

The chamber 30 is provided with an outlet 58 which is connected by a conduit 52 to a storage sac or bladder 54 secured to an extended portion 21 of the frame 20. A one-way valve 56 is connected in the conduit 52 adjacent the sac 54 so that liquid flowing from the chamber 30 cannot flow back through the conduit 52 if the doll is placed in a horizontal or upside-down position.

An outlet valve 58 is connected to the lower portion of the storage sac 54 and a conduit connects the valve 58 to an opening 60 in the lower portion of the body 10. A control lever 62 extends from the valve 58 to the exterior of the

body 10 so that fluid may be discharged from the sac 54 as required.

The eye moving portion of the apparatus is mounted on the top of the liquid receiving chamber 30 and comprises a support 70 which rotatably supports a counterbalanced shaft 72 on which are mounted a pair of doll's eyes 74. The shaft 72 is positioned relative to the eye openings 73 in the doll's head 12 so that the eyes are open when the doll is in the upright position, this position being determined by the engagement of a counterbalanced arm 78 projecting from the shaft 72 with a stop 80 extending from the support 70.

15 A cam 82 is mounted on a shaft 84 and is adapted to contact the counterbalance 78 at intervals so as to cause the eyes 74 to move up and down. The cam 82 is driven by a ratchet wheel 88 also mounted on the shaft 84, the shaft 84 being mounted between supports 90 extending from the upper surface of the chamber 30. A ratchet dog 92 is pivotally mounted on the extension 36 of the lever member 32 so that the upward movement of the lever 32 as caused by the pressing of the main lever 40 engages the dog 92 with the teeth of the ratchet wheel 88 and causes it to rotate.

20 A spring 96 is connected between the chamber 30 and the dog 92 so as to maintain the dog in engagement and a spring 98 engages the teeth of the wheel 88 so as to prevent reverse rotation. The cam 82 and the teeth of the ratchet wheel 88 are preferably proportionate so that a camming action occurs about every five strokes of the main lever 40. This has been found to produce an eye action that closely simulates the actions of a human infant while drinking from a nursing bottle.

25 For most efficient operation the nursing bottle used to supply liquid to the doll is preferably equipped with a special nipple 100 that includes a one-way check valve 102 as is shown in Figure 5. With this arrangement, the flow of liquid from the bottle to the nipple is shut off through the check valve 102 when the nipple end 106 is squeezed through the action of the lever depressor member 34, and the liquid contained in the nipple end 106 is expelled into the chamber 30 (see Figure 6). On release of the nipple end 106, the check valve 102 is also released and allows liquid to flow from the bottle into the nipple.

30 While it is understood that other forms of bottles and nipples might be employed it has been found that the type employing the check valve nipple is most efficient and eliminates undue leakage and spilling of the liquid when the nipple is withdrawn or inserted in the mouth opening of the doll.

We claim:

35 1. In combination with a doll having a hollow body and a hollow head connected to said body, said head including a mouth opening and said body including a discharge opening in the lower portion thereof; a liquid receiving apparatus comprising, an elongated supporting frame mounted within said hollow body and extending from adjacent the lower portion of said body into said head, a hollow member having top, side, and bottom walls constituting a liquid receiving chamber mounted on the upper end of said supporting frame within said doll head, said liquid receiving chamber having a laterally open end disposed adjacent the mouth opening of said doll head, the other end of said chamber being blocked 40 by a partition having therein a relatively small

discharge opening, a first lever member pivotally mounted on said supporting frame beneath and extending the length of said liquid receiving chamber, an extension of said first lever member projecting within said chamber body and being adapted for up and down movement between said side walls, a second lever member pivotally mounted on said supporting frame beneath said first lever member and being operatively connected thereto, said second lever member extending from adjacent said doll head to a pivotal connection with a flexible member inset in said doll body, a reservoir adapted to receive liquid from said liquid receiving chamber mounted on the lower end of said supporting frame and including a controlled outlet means connected to said doll body discharge opening, conduit means between said liquid receiving chamber discharge opening and said reservoir, and control means for said reservoir outlet disposed exteriorly of said doll body.

10

15

20

2. A combination as claimed in claim 1, where-in said doll head includes eye openings, a pair of artificial eyes mounted for pivotal movement on the top of said liquid receiving chamber in alignment with said eye openings and means operatively connecting said eyes to said first named lever member whereby fluctuation of said lever is adapted to cause intermittent movement of said eyes.
